UNITED STATES PATENT OFFICE

MAX FRITZ GUSTAV HOFFMANN, OF CHEMNITZ, GERMANY

INDICATOR

Application filed September 12, 1927, Serial No. 219,128, and in Germany September 24, 1926.

My invention relates to indicators and more particularly to indicators of the type in which movable parts, as bands or strips, bearing certain data, are displaced with respect to stationary marks, and it is an object of my invention to provide an appliance of the kind described which is simple, easy to manipulate and ready to survey.

To this end, I provide a set of bands or strips bearing certain data and a grid between the bars of which a certain portion of the bands, with the data on it, and indicating, for instance, the quantity of supply in stock, or any other data, becomes visible and the distance of such data from a stationary mark will indicate their variation. The bands are separated by the bars of the grid so that their data will be plainly discerned.

I may construct my indicator as a flat board or table, or as a casing surrounding a rotary cylinder on which the bands are wound. In the latter instance, I may provide on the cylinder indications of time, as the months of a year, and their days, and secure the ends of the bands to the cylinder in various positions so as to indicate the expiration of periods, as, for instance, delivery times. The cylinder is moved on as the time elapses and the period still available is read on a stationary mark.

In the accompanying drawings, indicators embodying my invention are illustrated by way of example.

Figs. 1 to 7 illustrate indicators constructed as boards or tables,

Figs. 8 to 11 illustrate an indicator having a rotary cylinder.

More particularly,

Fig. 1 is an elevation of an indicator for a single kind of indications,

Fig. 2 is a section on the line II—II in Fig. 1,

Fig. 3 is a section on the line III—III in Fig. 1, on a larger scale,

Figs. 4 and 4^a are detail views showing part of the upper and lower edges of the central plate in the table,

Fig. 5 is a section on the line V—V in Fig. 4,

Fig. 6 is an elevation of an indicator for

two types of indications, for instance, positive and negative data, on either side of a neutral or zero line,

Fig. 7 is a section on the line VII—VII in Fig. 6,

Fig. 8 is an elevation, partly broken away, of an indicator having a rotary drum,

Figs. 9, 10, and 11 are part sections on the lines IX—IX, X—X, and XI—XI in Fig. 8.

Referring now to Figs. 1 to 5, the board or table is built up from three plates, a back 1, a central plate 2 and a front plate or grid 3. 4 are endless bands supported on the central plate 2 and inserted in slots 6 near the upper edge of the plate, as shown in Fig. 4, and guided in recesses 7 at the lower edge of the plate, as shown in Fig. 4^a. The slots 6 are preferably staggered. 5 are narrow ridges formed on the central plate so as to extend along the edges of the bands on that reach which is exposed between the bars of the grid 3, and keep the bands from interfering. The two lateral edges of the plate 2 are offset as shown at 2' in Fig. 3, and are engaged by the correspondingly offset edges 1' of the back 1 so that the two edges are brought up to the border 3' of the grid 3.

The grid 3 is quite flat and comprises the two lateral edges 3', 3' referred to, an upper edge 3'', a lower edge 3''', and a set of vertical bars 9 extending between the upper and lower edges so as to partly expose the bands 4 between the bars. The three parts are connected by rivets 8 which may be hollow as shown, and serve for securing the board to a wall or other support.

The bands 4 are partly white or painted in some other light colour, and graduated or otherwise marked on the light fields, and those parts which are not graduated etc., are painted black or some other dark colour, and the face of the grid 3 is painted in the same dark colour so that the light portions of the bands, with their graduations etc., are plainly picked out. 10, 10 are cards or tickets inserted in a holder at the upper edge 3'' of the grid and bearing indications relating to the bands below them, and 11 is a flap hinged above the holder so as to conceal the tickets from inspection by unauthorized persons.

sons. 12 are a row of holes in the upper edge 3" which are preferably duplicated (not shown) in the lower edge 3'" and serve for the insertion of marking rods 13 if it is desired to designate certain bands for particular attention.

In operation, the bands 4 are so adjusted as to indicate certain data with reference to the tickets in the holder, for instance, the 10 supply in stock of goods. The extent to which the lighter portions of the bands are visible from the upper edges of the interstices of the bars 9 is a measure for the quantity or other datum indicated. It will be 15 understood that the bands will be moved in downward direction for adjusting them but I am not limited to this, as obviously the arrangement may be reversed without departing from my invention.

To facilitate the operation of the bands, 20 ridges or other projections 14, or holes 14', may be provided where the light portions border on the dark ones.

Particularly important indications are 25 picked out by rods 13, as described.

Referring now to Figs. 6 and 7, this board is substantially similar to the board described with reference to Figs. 1 to 5, and corresponding parts have been marked with the same 30 reference numerals. In this instance, however, the grid 3 is divided into an upper and lower field by a horizontal strip 15, and a set of bands 4' and 4'' is allotted to each field. The strip 15 constitutes the neutral or zero 35 line, and slots 6, 6 are formed in the central plate 2 beneath the strip. Similar slots 6 are formed below the upper edge 3", and recesses 7 are formed in the lower edge of the central plate 2 so that the bands 4' of the upper set 40 are guided in two slots 6, and the bands 4'' of the lower set are guided in a slot 6 and a recess 7, for each band. The bands 4' of the upper set make positive indications, that is, their light portions extend upwards from the 45 upper edge of the strip 15, and conversely, the bands 4'' make negative indications, their light portions extending downwards from the lower edge of the strip 15.

It follows that the positive or negative portion in each vertical column will be covered 50 up by the dark portions of the corresponding bands 4', 4'', as clearly shown in Fig. 6.

Referring now to Figs. 8 to 11, this indicator is equipped with a rotary cylinder 21. 55 42' is the base plate, and 22 are the end walls of a casing 38 in which the cylinder is carried and adapted to be rotated by a knurled handle 23. At one end the cylinder is provided with a graduation of some sort, for instance, dates. 25 are depressions in the cylinder, one for each step of the graduation, in the present instance, for each day of the year, or a shorter period. 26 is a spring catch on the casing 38 which is adapted to engage one 60 of the depressions 25 so that the cylinder 21

is arrested as often as it has been rotated through an interval of its graduation, in the present instance, through one day. 28 and 29 are sets of spring rollers carried on stationary shafts below the cylinder 21, and 30 and 31 70 are bands, one of which is carried on each roller of the sets 28 and 29, respectively. In the present instance, it will be assumed that the indicator is for dates of delivery of certain classes of goods inscribed on tickets 44 75 and generally indicated by the letters A, B, etc. on the casing 38. A pair of bands 30 and 31 corresponds to each class of goods. One of them, 30, which may be painted white, serves for indicating the end of the delivery period, 80 and the other, which may be yellow, or any other colour different from that of the band 30, serves for indicating an extension allowed on the period, if any. The surface of the cylinder 21 is painted in a third, preferably 85 dark, colour, so that the bands will be plainly observed.

Each band 30 and 31 is threaded through a slot 33 or 34 in a vertical stop plate 32 on the base plate 42' at the rear of roller sets 28, 90 29, and provided with a U-shaped bracket 35, 35', respectively, at its end which cannot pass through the slots in the plate 32. Springs, not shown, on each roller of the two sets, tend to rotate the rollers in the direction of the arrows 37, 37' so as to wind up the bands as far as the partition 32 permits.

The brackets at the ends of the bands 30, 31 are adapted to be inserted in holes 36 in the cylinder 21 which extend in parallel rows, 100 each corresponding to one day.

The casing 38 is divided at 43 and its front wall 39 as well as its rear wall 38' are adapted to be turned down on hinges 42 and 24, respectively. The hinge 42 at the front of the 105 casing is arranged at the top of a vertical plate, and above the hinge extends an inclined pulpit-like face 43' for the reception of the tickets 44 on which may be inscribed classes of goods, order Nos., and other information. 110

The front plate 39 is grid shaped for about one-fourth of the perimeter of the cylinder 21, and painted some dark colour, preferably black. The bands 30, 31 are exposed in the interstices of the grid bars 40. A bar 41, 115 painted some bright colour, as red, extends in front of the bars 40 and the cylinder 21 is rotated each day in the direction of the arrow 27, Fig. 9, so that the date indicated on its graduation corresponding to that day, appears below the "date" bar 41.

In operation, and assuming that a certain class of goods, "G", must be delivered on May 31st, the front and rear walls of the casing are turned down about their hinges 42 and 24, 120 the band 30 is unwound from its roller in the direction of the arrow 43 and its bracket 35 is inserted in the parallel row of holes 36 for May 31st. If an extension is permitted, the corresponding band 31 is also pulled out and 125 130

its bracket 35' is secured in the row of holes 36 for the extended period, and the casing is closed.

As the cylinder is moved forward each day, 5 it will become apparent at a glance how many days of the period are still open, and when the time is up, the bracket 35 will appear at the level of the "date" bar 41. If the delivery cannot be kept within time, the bracket 35 will 10 move beyond the "date" bar and, if an extension has been arranged for, the band 31 will now indicate its elapsing.

When the goods have been delivered, the 15 brackets 35, 35' are detached from the holes 36 in the cylinder 21, and the bands are then rewound on their rollers for further use. As mentioned, their brackets are retained by the plate 32.

I claim:

20 1. An indicator comprising a casing, a dark colored grid on said casing, and light colored flexible bands bearing indications and arranged side by side and adapted to be adjusted in parallel rows in said casing and to 25 be exposed in the interstices of the grid bars. 2. An indicator comprising a casing, a graduated support adapted to be displaced with respect to said casing, bands bearing inscriptions adapted to be secured at different 30 points to said support so as to partake in its movement, a grid on said casing in the interstices of which said bands are exposed, and a mark on said casing indicating the relative position of said graduated support and said 35 casing.

3. An indicator comprising a casing, a graduated support adapted to be displaced with respect to said casing, rollers carried to rotate in said casing, bands bearing inscriptions secured to said rollers and adapted to be temporarily connected with said support, means for returning the rollers to their initial 40 positions, a grid on said casing in the interstices of which said bands are exposed, and a mark on said casing indicating the relative 45 position of said graduated support and said casing.

4. An indicator comprising a casing, a graduated support adapted to be displaced with respect to said casing, rollers carried to rotate in said casing, said rollers being so made as to tend to return to their initial position, bands bearing inscriptions secured to 50 said rollers and adapted to be temporarily connected with said support, a grid on said casing in the interstices of which said bands are exposed, and a mark on said casing indicating the relative position of said graduated support and said casing.

5. An indicator comprising a casing, a graduated cylinder adapted to be rotated in said casing, bands bearing inscriptions having their inner ends mounted in the casing and adapted to be secured at their outer ends 55 at different points to said cylinder so as to

partake in its rotation, a grid on said casing in the interstices of which said bands are exposed, and a mark on said casing indicating the relative position of said cylinder and said casing.

6. An indicator comprising a casing having walls adapted to be opened out, a graduated support adapted to be displaced with respect to said casing, bands bearing inscriptions adapted to be secured to said support so as to partake in its movement, a grid on said casing in the interstices of which said bands are exposed, and a mark on said casing indicating the relative position of said graduated support and said casing.

7. An indicator comprising a casing, a graduated support adapted to be displaced with respect to said casing, bands bearing inscriptions adapted to be secured to said support so as to partake in its movement, projections on the ends of said bands, a slotted plate in said casing through which said bands are threaded so as to retain them by their extended ends, a grid on said casing in the interstices of which said bands are exposed, and a mark on said casing indicating the relative position of said graduated support and said casing.

8. An indicator comprising a casing, a graduated cylinder adapted to be rotated in said casing, bands bearing inscriptions adapted to be secured in parallel rows of holes in said cylinder so as to partake in its rotation, a grid on said casing in the interstices of which said bands are exposed, and a mark on said casing indicating the relative position of said cylinder and said casing.

9. An indicator comprising a casing, a grid on said casing, a plurality of flexible bands bearing indications and arranged in parallel rows in said casing, means for adjusting the bands in said casing so that the indications thereon will be exposed in the interstices of the grid, and means for returning the bands to their initial positions.

10. An indicator comprising a casing, a graduated support adapted to be displaced with respect to said casing, flexible bands bearing indications having the inner ends yieldably connected with the inner casing and adapted to be extended and having their outer ends temporarily secured at different points to said support so as to partake in its movement, means for returning the bands to their initial positions, a grid on said casing in the interstices of which said bands are exposed, and a mark on said casing indicating the relative position of said graduated support and said casing.

In testimony whereof I affix my signature.

MAX FRITZ GUSTAV HOFFMANN.
